DESIGN FOR A LADY'S COAT

Abraham Sisselman, New York, N. Y.

Application April 17, 1935, Serial No. 56,423

Term of patent 3½ years

To all whom it may concern:

Be it known that I, Abraham Sisselman, a citizen of the United States of America, residing in Manhattan, county of New York, and State of New York, have invented a new, original, and ornamental Design for a Lady's Coat, of which the following is a specification, reference being had to the accompanying drawing, forming part hereof, wherein,

I claim:

The ornamental design for a lady's coat, substantially as shown.

ABRAHAM SISSELMAN.
